UNITED STATES PATENT OFFICE.

CLAYTON D. COLLEY, OF COEBURN, VIRGINIA.

WRENCH.

SPECIFICATION forming part of Letters Patent No. 759,674, dated May 10, 1904.

Application filed September 22, 1903. Serial No. 174,177. (No model.)

To all whom it may concern:

Be it known that I, CLAYTON D. COLLEY, a citizen of the United States, residing at Coe-burn, in the county of Wise and State of Virginia, have invented a new and useful Wrench, of which the following is a specification.

This invention relates to implements of the class known as "quick-action" wrenches, and has for its object to simplify and improve devices of this character; and the invention consists in certain novel features of construction, as hereinafter shown and described, and specified in the claims.

In the drawings illustrative of the invention, in which corresponding parts are denoted by like designating characters, Figure 1 is a sectional side elevation of one of the improved wrenches. Fig. 2 is a sectional detail of the movable jaw, and Fig. 3 is a rear view of the movable jaw detached.

The improved implement comprises a stock 10, preferably with a handle 11 at one end and terminating at the other end in a laterally-extended stationary jaw 12 and with spaced transverse ratchet-teeth 13 on the rear side, as shown. Slidably disposed upon the stock 10 is a movable jaw 14, having extensions 15, 16, extending, respectively, in advance of its face and lower sides, as shown. The extension 15 is provided with internal ratchet-teeth 17, adapted for engagement with the teeth 13 when the outer or free end 18 of the movable jaw is tilted away from the jaw 12 or when the strain is applied, and thus "lock" the movable jaw to the stock, while at the same time the movable jaw can be quickly released by reversing the tilting movement. The movable jaw member is provided with a cavity 19 for supporting a spring 20, bearing against the inner face of the stock to maintain the movable jaw yieldably in operative position with the teeth 17 in engagement with the teeth 13. The extension 16 is curved outwardly, and the stock 10 is provided with a sleeve 21, slidably thereon and provided with a socket for the extension 16 and having a curved rear wall 22, corresponding to and engaging the curved outer surface of the portion 16, as shown in Fig. 1. By this simple arrangement the movable jaw

member 14, with its connected sleeve 21, may 50 be freely moved upon the stock 10 in one direction by slightly pressing the outer end 18 of the movable jaw 14 toward the stationary jaw 12, or by tilting the movable jaw upon the stock to compress the spring 20 and release 55 the teeth 17 from engagement with the teeth 13; but the movable jaw will be instantly locked rigidly in engagement with the stock when pressure is applied in the opposite direction to the movable jaw, as will be obvious. 60

When the movable jaw member is tilted to release it, the curved extension 16 will move freely longitudinally for a short distance in its socket in the sleeve 21 and upon the curved surface 22 and then carry the sleeve with it 65 in its sliding outward movement along the stock. The presence of the sleeve does not, therefore, interfere with the action of the movable jaw when the latter is being "set" to the nut or other object; but when the strain is applied the sleeve instantly becomes an important factor in the action of the implement as the curved portion 22 receives the rearward thrust of the extension 16 and divides the strains with the teeth 17 and 13. 75

The wrench is thus materially strengthened at a very slight addition to the weight and expense.

The parts will preferably be of steel and may be of any required size to provide for 80 the production of various sizes of wrenches.

Having thus described the invention, what I claim is—

1. A wrench comprising a stock terminating in a laterally-extended jaw and provided with 85 spaced transverse ratchet-teeth on the rear side, a movable jaw slidably disposed upon said stock and provided with an extension in advance of its face side having spaced teeth for engagement with the teeth of said stock 90 and with an extension disposed in advance of the opposite side and curved outwardly, and a sleeve slidably disposed upon said stock and having a socket to receive the curved extension of said movable jaw, substantially as described. 95

2. A wrench comprising a stock terminating in a laterally-extended jaw and provided with

spaced transverse ratchet-teeth on the rear side, a movable jaw slidably disposed upon said stock and provided with an extension in advance of its face side having spaced teeth for engagement with the teeth of said stock and with an extension disposed in advance of the opposite side and curved outwardly, and a sleeve slidably disposed upon said stock and having a socket to receive the curved extension of said movable jaw, and a spring be-

tween said movable jaw and the front side of said stock, substantially as described.

In testimony that I claim the foregoing as my own I have hereto affixed my signature in the presence of two witnesses.

CLAYTON D. COLLEY.
